BOTTLE OR SIMILAR ARTICLE

Victor Koenigsberg, Franklin Square, N.Y., assignor to Colgate-Palmolive Company, New York, N.Y., a corporation of Delaware

Filed Apr. 4, 1966, Ser. No. 1,755

Term of patent 14 years

(Cl. D58—6)

FIG. 1

FIG. 2

FIG. 4

FIG. 1 is a side elevational view of a bottle or similar article embodying my new design, the other side being substantially a mirror image thereof;

FIG. 2 is an end elevational view thereof, the other end being substantially a mirror image thereof;

FIG. 3 is a bottom plan view thereof; and

FIG. 4 is a top plan view thereof.

I claim:

The ornamental design for a bottle or similar article, as shown and described.
